UNITED STATES PATENT OFFICE.

OVERTON WINSTON, OF MINNEAPOLIS, MINNESOTA.

HEADLIGHT.

1,312,715.

Specification of Letters Patent.

Patented Aug. 12, 1919.

Application filed January 26, 1916, Serial No. 74,341. Renewed January 3, 1918. Serial No. 210,227.

To all whom it may concern:

Be it known that I, OVERTON WINSTON, a citizen of the United States, residing at Minneapolis, in the county of Hennepin and 5 State of Minnesota, have invented certain new and useful Improvements in Headlights; and I do hereby declare the following to be a full, clear, and exact description of the invention, such as will enable others 10 skilled in the art to which it appertains to make and use the same.

My present invention relates to electric headlights for automobiles and is in the nature of an improvement on, or modification 15 of the mechanism disclosed and claimed in my copending application S. N. 64,661, filed December 2nd, 1915, and entitled "Headlights."

Particularly, the invention is directed to 20 the improvement of means for shifting the electric light bulb in respect to the reflector, whereby the bulb may be adjusted, both axially of and transversely in respect to the axis of the reflector. The first noted adjustment is desirable to locate the lamp filament at the focal center of the reflector, and the latter noted adjustment is desirable, 25 to throw the filament of the lamp to and from the axis of the reflector. For example, in traveling country roads, powerful light beams of long projection are desirable, while for city travel, the light beams should be projected onto the road more closely in front 30 of the machine, so that there will be no upwardly projected blinding rays thrown into the eyes of persons in passing automobiles. The above noted adjustments also provide a simple and highly efficient way, and means 35 whereby high power headlights may be used without running into conflict with city ordinances directed against the use of blinding 40 headlights.

In the accompanying drawings which 45 illustrate the invention, like characters indicate like parts throughout the several views.

Referring to the drawings:

Figure 1 is a vertical section taken centrally through a headlight designed in accordance with my invention; 50 Fig. 2 is a detail view in rear elevation showing the lamp socket and opposing magnets and coöperating latches for moving and holding the same; and

Fig. 3 is a view partly in vertical section 55 and partly in diagram, illustrating the man-

ner in which the headlight may be wired or electrically connected.

The numeral 1 indicates the casing of an ordinary headlight, such as generally used on automobiles, and the numerals 2 and 3 indicate, respectively, the reflector and lens or glass plate of the headlight. The electric light bulb 4 illustrated is of the well known Edison single base type, but, of course, other types of bulbs may be employed. As shown, 60 however, the bulb has an outer contact sleeve 5 connected to a battery lead 6, and has an axial boss (not shown) connected to the other battery lead 6^a. Said leads 6 and 6^a are connected to the opposite terminals of a 65 battery 6^b, or other source of electrical energy, and a circuit closer 6^c, as shown, is interposed in the lead 6^a.

The lamp sleeve 5 is telescoped into a so-called lamp holding collar 7 that is seated 75 in the front end of the longitudinally adjustable section 8 of a so-called lamp socket made up of the said section 8 and a surrounding cylindrical shell 9.

The said lamp holding socket and means 80 for adjusting the lamp axially, are, or may be, of the construction illustrated in the said prior application above identified, and for the further purposes of this case, it need only be stated that the axial adjustment of 85 the socket section 8 and lamp, in respect to the socket section 9 may be accomplished by rotation of a nut 10 swiveled in the rear end of the said section 9, and having, in its rear end, notches 11 that are adapted to be 90 engaged by the flat inner end of a so-called screw driver, presently to be described, and which latter, except for important details, is like that of the said prior application.

The outer section or cylindrical shell 9 of 95 the lamp socket, at its front end, is freely surrounded by a hollow bearing head 12 that is detachably, but rigidly clamped to a flanged anchoring ring 13 rigid on the back of the reflector. Furthermore, the said lamp 100 socket is mounted for oscillatory movements in a vertical plane, and is pivotally connected at 14 to the sides of the head 12, by means of conical pointed screws, or other suitable horizontally extended laterally 105 spaced pivotal devices. Of course, the reflector has an axial passage through which the lamp socket projects to hold the bulb within the reflector.

The cylindrical outer shell 9 of the lamp 110

socket is either made of iron, so that it will serve as an armature in coöperation with electro-magnets, or it is, as shown and preferred, provided on its rear portion with a surrounding iron collar 15, which serves as an armature. This armature 15, at the lower portion of one side and at the upper portion of the other side, is formed with V-shaped lock detents or notches 16, for a purpose which will presently appear.

Located, one above and one below the armature-equipped rear end of the lamp socket, is a pair of opposing electro-magnets 17 that are rigidly supported by collars 18, of the hollow head 12. For coöperation with the armature 15 on the lamp socket, the magnets 17 are provided with pole pieces 19 which, to fit the rounded upper and lower surfaces of the said armature, are made correspondingly concave. The arrangement is such that, when the upper magnet is energized and the armature moved into contact with its pole piece, the filament of the bulb 4 will be on the axis of the reflector, but when the said lower magnet is energized and the armature is in engagement with the pole piece thereof, the filament of the bulb will be thrown above the axis of the reflector, as shown in Fig. 1.

30 A small coiled spring 20 is anchored at its lower end to the lower magnet, or other fixed base of reaction, and at its upper end is attached to a pin or finger 21 that projects rearward from the armature 15. This spring prevents or assists in preventing the lamp socket from vibrating and rattling in running over rough roads. Circuit connections are provided whereby either of the magnets 17 may be energized at will.

40 As shown, the said upper and lower magnets 17 are connected in multiple with the main circuit 6—6^a, by means of shunt circuits 22 having circuit closing devices 23, such as push buttons. Both shunt circuits 45 22 are open and both magnets deenergized.

For coöperation with the lock notches 16 in the socket armature 15, small latches 24 are intermediately pivoted to the magnet supporting collars 18. The lower end of the 50 lower latch 24 and the upper end of the upper latch 24 are laterally bent and serve as armatures that are subject to the outer end pole pieces of the coöperating magnets. The inner ends of the said latches are formed 55 with wedge-shaped lock lugs 25 for engagement with the respective notches 16. Light leaf springs 26, shown as applied on the magnet spools, act on the outer ends of the latches and yieldingly force the lock lugs 25

60 against the flat side faces of the armature 15 or into engagement with the coöperating notch 16. When the lamp socket is moved upward on its pivot 14, so as to set the lamp filament at the axis of the reflector, the lock 65 lug 25 of the lower latch will engage the

lower notch 16 and lock the said socket and lamp in such position. When, however, the lamp socket is dropped, as shown in Fig. 1, the lock lug 25 of the upper lever will engage the upper notch 16, and thereby lock 70 the lamp socket in its lowered position and the lamp bulb with its filament raised above the axis of the reflector.

By pressing one or the other of the push buttons 23, either of the magnets 17 may be 75 energized at will. Assume, for illustration that the lamp socket is in its lower position and that the lamp bulb is raised, as shown in Figs. 1 and 2, and that the upper magnet is then energized, by pressing the coöperating 80 push button 23. The said upper magnet operating on the armature 15 will raise the lamp socket until it strikes the pole piece 19, in which position the filament of the bulb will be moved to the axis of the reflector; 85 but the first effect of energizing the said upper magnet was to cause it to release the upper latch 24, so that the above noted movement of the lamp socket could take place. It is, therefore, evident that the one 90 latch, or the other will positively hold the lamp socket in the position into which it has been moved by energizing but one of the magnets, so that it is not necessary to energize either magnet for more than an instant 95 in order to effect the desired adjustment of the lamp.

The purpose of making the notches 16 and lock lugs 25 V-shaped or tapered, is to cause them to take up play and to always accurately position the lamp socket. It will, of course, be understood that, in practice, the circuit closers 6^a and 23 may be conveniently located on the instrument board of the automobile.

When the lamp socket is in its raised position, its axis will, of course, be coincident with the axis of the reflector; and in such position, its notched head or nut 10 is adapted to be engaged by a flat inner end 11^a or blade of a small so-called screw driver 27 that is mounted to rotate and to move axially in a bearing sleeve 28 secured to the back of the casing 1 in line with the axis of the reflector. In its outer end, this screw 11^b driver 27 has a knurled head 29 that is adapted to be engaged by a spring finger 30 secured to the sleeve 28. This spring finger 30 holds the screw driver frictionally against accidental rotary and axial movements, but permits such movements to be given to said screw driver by a force applied by the fingers and thumb to the knurled head thereof.

What I claim is:

1. In a headlight, the combination with a casing, of a reflector supported thereby and spaced therefrom, of a lamp socket pivotally supported from said reflector and projecting into the space between said reflector and cas- 130

- ing, and an electro-magnet for oscillating said socket supported entirely from the back of said reflector, said magnet and the pivotal connection between said socket and reflector 5 being unaffected by movement of said casing in respect to said reflector.
2. In a headlight, the combination with a reflector and a lamp socket pivotally mounted for movements in respect to the axis 10 of said reflector and having at the rear of its pivot an element serving as an armature, upper and lower lock levers operative to hold said socket, respectively, in lowered and raised positions, and upper and lower electro-magnets operative, the former to release 15 said upper lock and raise said socket, and the latter to release said lower lock and lower said socket.
3. In a headlight, the combination with a reflector, of a lamp socket having at its front end means for holding a light bulb within said reflector, said socket being mounted for vertical pivotal movements so as to carry the filament of said bulb to and 20 from the axis of said reflector, and having an armature at the rear of its pivot, and upper and lower electro-magnets operative on said armature and having pole pieces of the same form as the engaging surfaces of said armature. 25
4. In a headlight, the combination with a reflector, of a lamp socket having at its front end means for holding a light bulb within said reflector, said socket being pivoted for 30 vertical movements and having an armature at the rear of its pivot, of upper and lower electro-magnets co-operating with said armature to raise and lower said socket, and an anchored spring connected to said socket 35 and normally holding the same in one extreme position when the magnets are de-energized, and locks for holding said socket in its two positions, which locks are arranged to be released, one by each of said magnets. 40
5. In a headlight, the combination with a reflector and a lamp socket that is pivoted for vertical movement in respect to the axis thereof, of stops for limiting the upward and downward movements of said socket, 45 upper and lower locks for securing said socket, respectively, in lowered and raised positions, lower and upper magnets, the former serving to release said lower lock and the latter serving to release said upper lock 50
- and raise said socket, and a spring normally holding said socket against said lower stop. 55
6. In a headlight, the combination with a reflector and a lamp socket that is pivoted for vertical movement in respect to the axis thereof, said socket having lock detents on its opposite sides, upper and lower lock levers having lock lugs at one end and armatures at the other other, said lock lugs being alternately engageable with the detents of said socket, upper and lower electro-magnets, the upper magnet being operative, first to release the upper lock and then to move said socket upward, and said lower magnet being operative, first to release said lower lock and then to move said socket downward. 60 70
7. In a headlight, the combination with a reflector, of a lamp socket that is movable vertically in respect to the axis thereof, of upper and lower electro-magnets operative on said socket, respectively, to move the same upward and downward, an electric light bulb carried by said socket, a source of electrical energy, a circuit including said source and said light bulb, and shunt circuits from the said light bulb circuit including 75 said electro-magnets, said shunts having normally open, independently operable circuit closers. 80
8. In a headlight, the combination with a reflector and a lamp socket pivotally associated therewith, of an electro-magnet for moving said lamp socket, said magnet having a pole piece serving as a stop to limit the movement of said socket toward said magnet, and one element of said socket serving 85 as an armature upon which said electro-magnet directly acts. 90
9. In a headlight, the combination with a reflector, of a pivotally mounted lamp supporting socket, one element of which serves 95 as an armature, and an electro-magnet having a pole piece serving as a stop for limiting the movement of said armature toward said magnet, the stop surface of said pole piece having the same form as the engaging 100 portion of the armature acting element of said socket.

In testimony whereof I affix my signature in presence of two witnesses.

OVERTON WINSTON.
